United States Patent

Des. 240,755

Patented July 27, 1976

240,755

WINDOW GREENHOUSE

Charles Wheeler Clark, Dumont, and Charles Melvin Dye, Wyckoff, N.J., assignors to RCA Corporation

Filed Oct. 1, 1975, Ser. No. 618,491

Term of patent 14 years

Int. Cl. D11—02

U.S. Cl. D35—3 R

Fig. 1.

Fig. 2.

Fig. 3.

Fig. 4.

Fig. 5.

Fig. 6.

FIG. 1 is a perspective view of a window greenhouse, showing our design,

FIG. 2 is a top plan view thereof,

FIG. 3 is a front elevation view thereof,

FIG. 4 is a bottom plan view thereof,

FIG. 5 is a right side elevation thereof, the left side elevation being a mirror image of said right side elevation, and

FIG. 6 is a rear elevation thereof.

We claim:

The ornamental design for a window greenhouse, as shown and described.
